DESIGN FOR A COMBINATION DESK UNIT

Raymond S. Huss, Bala-Cynwyd, Pa.

Application June 29, 1939, Serial No. 85,756

Term of patent 14 years

To all whom it may concern:

Be it known that I, Raymond S. Huss, a citizen of the United States of America, residing at Bala-Cynwyd, in the county of Montgomery and State of Pennsylvania, have invented a new, original, and ornamental Design for a Combination Desk Unit, of which the following is a specification, reference being had to the accompanying drawing, forming part thereof.

Of the drawing,
Fig. I is a perspective view of a combination desk unit showing my new design;
Fig. II is a side elevation; and
Fig. III is a plan view of the same.

I claim:

The ornamental design for a combination desk unit, as shown.

RAYMOND S. HUSS.
